CLAIM

The ornamental design for a two-sided sign, as shown and described.

DESCRIPTION

FIG. 1 is an isometric view of a two-sided sign, showing our new design;

FIG. 2 is a front plan view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings are included for purposes of illustrating portions of the two-sided sign and form no part of the claimed embodiment.
